ASA IVY ALBRIGHT AND FRANCIS LAMAR MYATT, OF MONROE, LOUISIANA.

RIVETING-TOOL.

1,384,374.

Specification of Letters Patent. Patented July 12, 1921.

Application filed June 24, 1920. Serial No. 391,469.

To all whom it may concern:

Be it known that we, ASA IVY ALBRIGHT and FRANCIS LAMAR MYATT, citizens of the United States, and residents of Monroe, in 5 the parish of Ouachita and State of Louisiana, have invented a new and useful Improvement in Riveting-Tools, of which the following is a specification.

The present invention relates generally to 10 riveting tools and more particularly to an improved rivet holder or dolly adapted to hold the made head of a rivet while the other end is being headed.

The object of the invention is to provide 15 an improved rivet holder which is especially adapted for use with channel members or the like, as for instance in the assembling of the end cross members and the side members of an automobile chassis.

20 Another object is to provide an improved rivet holder of this character, of simple and durable construction, comparatively easy and inexpensive to manufacture and highly reliable and efficient in operation.

25 Other objects and advantages reside in the certain novel features of the construction, arrangement and combination of parts which will be hereinafter more fully described and particularly pointed out in the 30 appended claims, reference being had to the accompanying drawing forming part of this specification, and in which—

Figure 1 is a perspective view of the improved rivet holder in use,

35 Fig. 2 is a transverse vertical section adjacent the adjusting screw,

Fig. 3 is a fragmentary view in longitudinal vertical section adjacent the loose connection,

40 Fig. 4 is a fragmentary view in longitudinal vertical section of the active end or head of the dolly-bar and associated structures,

Fig. 5 is a fragmentary detail view illustrating a different use.

Referring to the drawings it will be seen that the invention is preferably used in connection with channel members or similar structures as for instance, with a chassis of 50 an automobile, the side members of which are indicated at A and B respectively, and one of the end cross members of which is indicated at C. The end cross member has its extremities extended over and riveted to the 55 lower flange a and b of the respective channel members and has a strap connection D

provided with an inturned end d which lies against and is adapted to be riveted to the upper flanges a' and b' of the side members A and B.

60 The bed plate or support 5 of the rivet holder has its ends resting upon the lower flanges a and b of the side members and is thus supported in position. As shown in the drawings, the bed plate is arranged to 65 lie in vertical alinement with the rivets to be headed.

A dolly-bar 6 is carried by the bed plate. One end of the dolly-bar is provided with 70 an opening 7, the walls of which are convexed so that the diameter of the opening increases from its center toward each of its ends. An opening 8 of uniform cross section is provided in the bed plate and the openings 7 and 8 are arranged to register. 75 A connecting bolt 9 is inserted through the openings 7 and 8, the head 10 of the bolt bearing against the upper surface of the dolly-bar and a nut 11 threaded upon the shank of the bolt bearing upon the under- 80 surface of the bed plate to secure the dolly- bar to the bed plate. However, the bolt 9 is of such length and the opening 7 of the dolly-bar is of such form that the dolly-bar may be freely moved vertically as well as 85 horizontally with respect to the bed plate, although positively prevented from partaking of any longitudinal movement with respect to the bed plate. The bolt 9 thus affords a loose connection between the dolly- 90 bar and the bed plate.

The opposite end of the dolly-bar from the loose connection constitutes the active end or head and is indicated at 12. Intermediate the head 12 and the loose connection the 95 dolly-bar is provided with an enlargement 13 having a threaded opening therethrough. A heavy adjusting screw 14 is operatively mounted in the opening and has its lower end mounted as at 15 and engaging the bed plate and carries a handle 16 at its upper end.

In operation the bed plate is first positioned on the flanges of the channel member and the head of the dolly-bar is then 105 moved to engage the made head of the rivet as indicated in Fig. 4, this adjustment of the dolly-bar being effected by a suitable operation of the adjusting screw. The adjusting screw may be so set as to clamp the 110 rivets in position and it is to be noted that it is not necessary to provide the head of the

dolly-bar with cups or recesses as this clamping action suffices.

As shown in Fig. 5 the extremity of the bed plate may be also made to constitute a 5 dolly head as indicated at 17, and in this arrangement we have a double dolly action so that both the head 12 and the head 17 "buck up" or hold the made head of the rivets while the other structure of the bed 10 plate and dolly-bar coöperate with the adjusting screw to provide the abutting or reactive force.

The loose connection afforded by the connecting rod 9, its head, nut 11 and the opening 8 of the dolly-bar constitutes an important feature of the present invention in that it provides for such movements of the dolly-bar as may be necessary to place it in position with its head holding the made 20 head of the rivet. It is to be noted, however, that after the dolly-bar is set in desired position the action of the adjusting screw 14 which clamps it in this position may be supplemented by tightening up the 25 nut 11 and thereby converting the normally loose connection into a substantially rigid one.

We claim:—

1. A rivet holder adapted for use with 30 channel members comprising a bed plate adapted to rest upon one of the flanges of the channel member, a dolly-bar carried by the bed plate and having an opening in one end and a head formed at its opposite end, a 35 loose connection between the dolly-bar and the bed plate comprising a bolt extending through the aperture of the dolly-bar, and

an adjusting screw carried by the dolly intermediate the loose connection and the head and operatively engaging the bed plate. 40

2. In a rivet holder of the character described, a bed plate, a dolly-bar, a loose connection between one end of the dolly-bar and the bed plate and an adjusting screw carried by the dolly-bar and operatively engaging 45 the bed plate.

3. A rivet holder adapted for use with channel members comprising a bed plate adapted to rest upon one of the flanges of the channel member, a dolly-bar carried by 50 the bed plate and having an opening in one end and a head formed at its opposite end, a loose connection between the dolly-bar and the bed plate comprising a bolt extending through the aperture of the dolly-bar, and 55 means for adjusting and maintaining the dolly-bar in desired position relative to the bed plate.

4. In a rivet holder of the character described, a support, a dolly-bar having one 60 end connected to the support and the other end constituting a head, and an adjusting screw carried by the dolly-bar and operatively engaging the support.

5. In a rivet holder of the character described, a bed plate having an end constituting a head for holding a rivet, a dolly-bar having one end connected to the bed plate and the other end constituting a head for holding a rivet and an adjustable screw carried by the dolly-bar and operatively engaging the support. 65 70
